UNITED STATES PATENT OFFICE.

RALPH ALBERTO CLARKE, OF ST. ALBANS, VERMONT, ASSIGNOR TO FRANKLIN RADIO COMPANY, OF ST. ALBANS, VERMONT, A CORPORATION OF VERMONT.

SPRING JACK.

Application filed January 14, 1924. Serial No. 686,094.

This invention relates to certain new and useful improvements in spring jacks which are particularly adapted for use with radio-communication circuits and apparatus. Particularly in the small and semi-portable apparatus used for receiving, it is well known that space is limited and that for selectivity, it is necessary to reduce the capacitive effects between the conductive portions of the apparatus. Such apparatus often have one or more stages of amplification, and it is customary to couple the reproducing instrument to the apparatus proper by the use of a spring jack for each stage, to receive a plug member connected to the reproducer; and to provide contact members in the jack to control the circuits in the apparatus. Owing to the large areas and short distances used in currently manufactured jacks, a high capacitive effect exists, to the serious impairment of the selectivity of the apparatus.

It is therefore an object of this invention to so design and arrange the elements of the spring jack as to produce an article which occupies slight space, is cheap in manufacture and easy to mount, has its terminals disposed for easy connection into a circuit, has no insulating member subject to wear, has its several elements spaced apart and having relatively small capacitive surfaces, is readily adapted to the various circuits, and is shielded against body-capacity effects.

In the accompanying drawings are shown several modifications of the application of this jack construction for use with various circuits. Fig. 1 is an open circuit jack. Fig. 2 is a double circuit jack. Fig. 3 is a jack similar to that of Fig. 2 but with an additional auxiliary blade. Figs. 4 and 5 are respectively a cross-section on line 4-4 of Fig. 2, and a side view of the jack with the panel in section.

My improved spring jack comprises a metal supporting member 1 with an insulating base block 2 thereon to receive and maintain electrically insulated from each other the various blade and terminal elements. A threaded aperture 3 through these members serves to receive the threaded plug sleeve 4, which passes through the customary panel board 5 of bakelite or the like, to hold the member 1 in place by clamping it tightly to the panel board. A screw 6 may likewise be used for this purpose.

Mounted on this insulating block 2 and

fastened thereto by binding posts and screws 7 and 8 are the various spring blades 9, 10, 11, 12 of the several figures. Binding post screws 7 are insulated from and recessed in apertures 13 of the metal plate 1; while screw 8 is in electrical connection with the spring blade 10 which makes contact with the plug sleeve element, and with the metal plate 1. The blades may be easily manufactured by punching substantially L-shaped blanks from sheet metal and then bending them to the proper form. The attaching foot 14 is formed by bending one leg of the blank out of its plane; and the other leg or major portion of the spring blade has its major axis disposed chordally with regard to the circular base, and substantially radial with regard to the plug sleeve 4. The outer ends of blades intended to come into contact with the plug are provided with offset ramps or cam surfaces 15, 16 running substantially parallel to the major axis and extending into the path of the plug, and are adapted to be engaged and moved laterally thereby, thus moving the blade in a plane parallel to the base. These cam surfaces 15, 16 are disposed at different planes with regard to the base, so one of them makes contact with the ball-point and the other with the sleeve on the plug. In order to assure the plug against accidental withdrawal and to afford a proper contact, a ridge 17 or 18 respectively is provided to engage the groove of the plug.

To cooperate with these spring blades are provided terminal members 19 which are similarly cut out and formed by punching operations. They are each provided with a small projection or contact point 20 of tungsten or the like to assure regular contact with the blade element. The ends of the terminal elements are bent and fastened to the insulating base block 2 by means of binding posts and screws 21 which are insulated from the metal plate and recessed in apertures similar to 13.

The wires used to connect the jack in the circuit or circuits are clamped in the binding posts at 7, 8, and 21. It will be noted that these posts may be set at any angle to avoid bends in the wires.

Only a very small area of the terminal member and of the spring blade are opposite each other, which assures a very low capacity when the jack opens the circuit upon the insertion of the plug. The spring blades tend

to bend for their whole length in a plane parallel to the base, instead of bending only at the line of contact with the base, which assures a long life and full flexibility.

5 The various figures show the applicability of the construction of various types of jacks. In Fig. 1 is a so-called single circuit jack. The plug has but a single contact member which cooperates with the spring blade 9. 10 This blade opens a circuit by moving away from the contact point 20 when the plug is introduced.

In Figs. 2, 4 and 5 is a more complex type, with two moving blades to make contact respectively with the ball-tip and the sleeve of a standard plug, as shown in Fig. 5. In this case each blade opens a circuit upon the introduction of the plug. The system allows a wide separation of the spring blades and the terminal members.

Fig. 3 shows a still more complex type, indicating the possibilities of assembly on a base of a single size. In this case the two right-hand spring blades function as in Fig. 2, but in addition to this, an insulating pillar 22 is added, between the spring blade 11 and the auxiliary spring blade 12. This latter spring blade has no direct electrical or mechanical connection with the other blades or the plug except by this pillar; it controls two circuits, one being open when the plug is in the jack, and the other being open when the plug is withdrawn. As before a wide space is presented between the blades and terminal members.

These modifications of the application of the new principle of construction indicate its adaptability to the various types of jacks which are required for various circuit combinations.

I claim:

1. In a spring jack, a base and a spring blade held substantially at right angles to said base and having an integral laterally offset supporting portion with a bent foot secured to said base, said blade having a plug receiving portion and adapted to be bent by such plug upon insertion into the jack in a direction substantially parallel to the plane of said base.

2. In a spring jack, a base, a spring contact blade held substantially at right angles

to said base and having an integral offset supporting portion with a bent foot secured to said base, said blade having a plug receiving portion and adapted to be bent by such plug upon insertion into the jack in a direction substantially parallel to the plane of the said base, and a cooperating terminal member upstanding from said base at a substantial angle to said blade, said blade and member being insulated from each other.

3. In a spring jack, a base having an aperture therethrough at substantially right angles to its plane, and a plurality of spring blades each held substantially at right angles to said base and having an integral laterally offset supporting portion with a bent foot secured to said base, each of said blades having a plug receiving portion and adapted to be bent by such plug upon insertion into the jack in a direction substantially parallel to the plane of the said base, said blades being insulated from each other and converging from their respective securing points to present their respective plug receiving portions opposite said aperture at different distances from the plane of said base.

4. In a spring jack, an insulating base member having a plug sleeve eccentrically mounted therein, a spring blade mounted on said base and extending chordally across said base and presenting its free end opposite said sleeve and being adapted to move in a plane substantially at right angles to the axis of said sleeve.

5. In a spring jack, an insulating base member having a plug sleeve mounted therein, and a plurality of spring blades mounted for resiliency in a plane substantially parallel to said base and converging towards said sleeve.

6. In a spring jack, an insulating base, a plug sleeve mounted in said base, a plurality of insulated spring blades mounted by lateral feet on said base and having cam surfaces thereon opposite said sleeve, the cam surfaces on said blades being disposed in different planes substantially parallel to said base, and said blades being disposed for resiliency in said planes.

In testimony whereof, I affix my signature.

RALPH ALBERTO CLARKE.
